UNITED STATES PATENT OFFICE.

GIUSEPPE ERARIO, OF NEW YORK, N. Y.

SWIMMING DEVICE.

Application filed January 31, 1924. Serial No. 689,753.

To all whom it may concern:

Be it known that I, GIUSEPPE ERARIO, a subject of the King of Italy, residing at New York, in the county of New York and State of New York, have invented certain new and useful Improvements in Swimming Devices, of which the following is a specification.

This invention relates to certain new and useful improvements in swimming devices and particularly to the kind that are adapted to be worn upon the feet of a person and constructed in a manner to cause an increased propelling action of the feet of a person during the act of swimming upon rearward movement of the feet.

The primary object of the invention is to provide a swimming device adapted for attachment to the seat in the general form of a sandal wherein side wings or paddles carried by a central foot or sole portion in a manner to be normally maintained in a plane above the central sole portion to permit usual walking movement with the side blades or paddles out of the way when entering and leaving water.

With the above and other objects in view that will become apparent during the course of the following description, the same consists of the novel form, combination and arrangement of parts hereinafter more fully described, shown in the accompanying drawing and claimed.

In the drawing, wherein like reference characters designate corresponding parts throughout the several views,

Figure 1 is a top plan view of a swimming device constructed in accordance with the present invention showing the side blades or paddles extended from the central sandal base or sole to operative position,

Figure 2 is a longitudinal sectional view taken on line II—II of Fig. 1,

Figure 3 is a cross-sectional view taken on line III—III of Fig. 1 showing the elastic tape for normally holding the side blades elevated above the horizontal plane of the sandal base or sole, and

Figure 4 is an enlarged detail sectional view showing the connection between one of the side blades and sandal base.

Referring more in detail to the accompanying drawing, there is illustrated a swimming device adapted for attachment to the foot of a person embodying a central sole for the base 1 constructed of any

material desired, such as wood or cork and to which a flexible sandal 2 formed of leather or the like is suitably secured, the sandal 2 including a strap and buckle connection 3 for fastening the same over the instep of the foot.

A side blade or wing 4 is hinged at spaced points as at 5 to each side edge of the central base 1 and has the hinged edge thereof cut at an angle as clearly shown in Figs. 3 and 4 so that when said angularly cut edge flatly abuts the adjacent edge of the central base 1, the wing 4 will be slightly elevated above the horizontal plane 60 of the base 1 which will permit free walking movement by a person wearing the swimming device upon entering and leaving the water.

To retain the side wings 4 in a slightly elevated position with respect to the central base 1 as shown in Figs. 3 and 4, the central base and side wings are provided with registering channels 6 and 7 respectively through which elastic tapes 8 extend, one or more of the elastic tapes being provided and anchored intermediate their ends in the central base 1 by the stud screw 9 as shown in Fig. 3 while the elastic tapes 8 are maintained under tension by the wedge pins 10 forced into the outer ends of the channels 7 and engaging the adjacent end of the elastic tape. The lower faces of the wings 4 are corrugated in an outward direction as at 11 tending to resist water pressure and to enhance the propelling force thereof.

A swimming device is mounted upon each foot of a person and as illustrated by full lines in Figs. 1 and 3, the side wings 4 are slightly elevated above the lower plane of the central base 1 permitting free walking movements of a person wearing the swimming devices unhindered by the side wings 4. During the swimming operation, the forward movement of the leg and foot through the water will cause the side wings 4 to move to the dotted line positions shown in Fig. 3 and when the foot is rearwardly projected, the wings 4 will be opened to extended positions offering greater resistance and increased propelling force, the corrugated lower face of the wings cutting the water and immediately increasing the propelling force at the instant of opening 110 movement thereof.

While there is herein shown and de-

scribed the preferred embodiment of the present invention, it is nevertheless to be understood that minor changes may be made therein without departing from the spirit and scope thereof as claimed.

What is claimed as new is:—

1. In a swimming device, a central base, a sandal carried thereby, and side wings hinged to opposite side edges of the base 10 with the edges thereof abutting the opposite sides of the base angularly cut to permit the wings to lie in a plane above the lower face of the base and means for holding the wings in an elevated position.
- 15 2. In a swimming device, a central base, a sandal carried thereby, and side wings hinged to opposite side edges of the base with the edges thereof abutting the opposite sides of the base angularly cut to permit the wings to lie in a plane above the 20 lower face of the base and means for holding the wings in an elevated position.

lower face of the base and elastic means for holding the wings in an elevated position.

3. In a swimming device, a central base, a sandal carried thereby, and side wings 25 hinged to opposite side edges of the base with the edges thereof abutting the opposite sides of the base angularly cut to permit the wings to lie in a plane above the lower face of the base, said base and wings 30 having registering channels extending transversely thereof, and elastic tapes extending through the channels and anchored at their ends at the outer edges of the wings for holding the wings in an elevated position.

In testimony whereof I affix my signature.

GIUSEPPE ERARIO.
